UNITED STATES PATENT OFFICE.

DANIEL O'HARA, OF WALTHAM, MASSACHUSETTS.

WATCH-CASE.

SPECIFICATION forming part of Letters Patent No. 298,615, dated May 13, 1884.

Application filed December 31, 1883. (No model.)

To all whom it may concern:

Be it known that I, DANIEL O'HARA, of Waltham, in the county of Middlesex and State of Massachusetts, have invented certain new and useful Improvements in Watch-Cases, of which the following is a full, clear, and exact description.

This invention, in substance, consists, first, of a band or ring to contain the movement, arranged therein in the usual or any other suitable manner, in combination with a central shell or body of the watch-case, which surrounds said movement-ring, and therewith constitutes one piece, either of the same metal or of different metals, or of other suitable material, and either by both being made of one piece or of separate pieces permanently secured together by soldering or otherwise, and is provided with an inner recess or chamber about said movement-ring, and which at its back and front is suitably adapted for the attachment of the other parts of the case necessary to complete it, all substantially as hereinafter described; second, of a band or ring to contain the movement, arranged therein in the usual or any other suitable manner, and of a central shell or body of the case, which surrounds said movement-ring, and therewith constitutes one piece, either of the same metal or of different metals, or of other suitable material, and either by both being made of one piece or of separate pieces permanently secured together by soldering or otherwise, and is provided with an inner recess or chamber about and outside of said movement-ring, in combination with the case-springs for the front plate or cap or cover of the watch-case, which are located within said recess or chamber about said movement-ring, and with said front and a back cover, the front hinged to said shell and arranged with said springs, to be opened by one and to be held closed by the other until released, and the back secured to said shell in any suitable manner, all substantially as hereinafter described; third, of a band or ring to contain the movement, arranged therein in the usual manner, in combination with a central shell or body of the case surrounding said ring, and constructed with a recess or chamber to receive and hold the case-springs for the front plate or cap or

cover of the case, and otherwise for said springs to be inserted in and removed from said recess, substantially as hereinafter described; fourth, of a band or ring to contain the movement, arranged therein in the usual manner, of a central shell or body of the case surrounding said ring, and constructed with a recess or chamber to receive and hold the case-springs for the front plate or cap or cover of the case, and at its front having said front cover hinged thereto and otherwise arranged to be opened by one of said springs and to be kept closed by the other, and at its back a cap or cover applied in any suitable manner, in combination with a ring to cover said springs in said recess, all substantially as hereinafter described; fifth, of a band or ring to contain the movement, arranged therein in the usual or any other suitable manner, in combination with a central shell or body of the watch-case, which surrounds said movement-ring, and therewith constitutes one piece, either of the same metal or of different metals, or of other suitable material, and either by both being made of one piece or of separate pieces permanently secured together by soldering or otherwise, and is provided with an inner recess or chamber about said movement-ring, adapted to be opened and closed, and which shell at its back and front is suitably adapted for the attachment of the other parts of the case necessary to complete it, all substantially as hereinafter described; sixth, of a back bezel or crystal-cap made in one piece with the back of the central shell or body of the case; seventh, of a front bezel or crystal-cap, in combination with a riser at the front of the central shell or body of the case, which riser and said cap are constructed for said cap to be entered into and secured to said riser, all substantially as hereinafter described; eighth, of a plate to be used for an outside cover or cap-plate of a watch-case, having its outer edge projected or bent or shouldered, all by stamping or turning, or in any other manner, and made of one piece of metal or other suitable material; ninth, of a recessed central shell or body and a movement ring or band in one piece, combined with other parts belonging to a watch-case, all substantially as hereinafter described; tenth, in a watch-case, the combination, with the wind-

ing-arbor of its watch-movement, of an arbor engaging therewith and arranged otherwise to be turned from the outside of the case, and thereby to turn said winding-arbor; eleventh, 5 in a watch-case, the combination, with the winding-arbor of its movement, of an arbor engaging therewith, and in turn engaged with a stem capable of being turned from the outside of the case, and all otherwise arranged 10 and combined with the case and movement substantially as hereinafter described.

The figures of the accompanying plate of drawings, forming a part of this specification, are on a similarly-enlarged scale, except Fig. 15 1^A, which is on a scale larger than the others.

Figure 1 is a transverse central section of a watch-case with all of its parts complete, except that only the dial-face and the winding-arbor of the watch-movement are shown, and 20 through the axial line of its pendant. Fig. 1^A is a similar section to Fig. 1, showing only the mechanism through which the watch-movement is to be wound, and the catch-spring for the front cap or plate of the case is to be 25 released from the outside of the case. Fig. 2 is a face view of Fig. 1 with the back cap or plate and other parts of the case removed, so as to show the arrangement and location of the case-springs within the recess of the central 30 shell or body of the case. Fig. 3 is a similar section to Fig. 1, showing only the mechanism through which the watch-movement is to be wound, and the catch-spring for the front cap or plate of the case released, from the 35 outside of the case, and for the purpose of illustrating a modification in the construction of said mechanism, as shown in Figs. 1, 1^A. Figs. 4 to 10, both inclusive, are sectional views, at one side only, of watch-case, and are 40 all in illustration of this invention in its relation to the construction of the central shell or body, and movement ring or band, and other parts, making therewith the case proper, all as will hereinafter fully appear.

45 In the drawings, A is the band or ring containing the watch-movement; B, the central shell or body; C, the front bezel-ring, and D its crystal; E, the back bezel-ring, and F its crystal; G, the front cap or plate; H, the back 50 cap or plate; J, the pendant, and K K² the case-springs—K being the opening-spring and K² the catch-spring for the front plate or cap G. The movement band or ring A, interiorly, is adapted, in any of the usual ways or in any 55 other suitable way, for receiving and securing the watch-movement represented in the drawings only by the dial-plate L and winding-arbor a, the latter projecting through an opening, b, in said movement-ring A, and in a line 60 having its axis coincident with the axis of the pendant J. This ring A, exteriorly, is surrounded by the central shell or body, B, having a recess or chamber, M. The central shell, B, and movement-ring A are either made 65 of one piece of metal or of other suitable material, or of separate pieces of the same metal

or of different metals or materials, secured together by solder or otherwise in any suitable manner, and all so that the same together shall constitute, in fact, one piece of the case, which, combined with the other parts for the attachment of which said shell is adapted, will secure the complete watch-case desired, as will hereinafter fully appear. The recessed shell B, above described, and either of itself 70 or together with the movement-ring A, may be stamped or pressed or turned out of the metal or other material of which it is to be made, or otherwise produced in any suitable manner; and if the recessed body or shell B and movement-ring A are to be made of separate pieces of metal and attached together, the ring may be made of a metal which is baser or cheaper than that which would be required for the shell. The recess or chamber M of 85 the central shell or body, B, is to be entered from the outside of the shell, and to render the shell capable of being so entered it can be left open either at its back N, Figs. 1, 3, 4, 8, 9, and 10, or at its front O, Fig. 6, or at 90 its outer edge or top, P, Fig. 5, or made in two halves, Q Q²—the one part, Q, including the movement-ring A, and it and the other, Q², adapted to be screwed together, Fig. 7. The open sides of the central shell, B, above 95 referred to, Figs. 1, 3, 4, 5, 6, 8, and 9, are closed by a ring, constructed in each instance to suit the side of the central shell which it is to close, and to complete the formation of the central shell at such side and preferably as 100 is shown, said closing-ring is attached to the shell by screwing it thereon, although, as is obvious, the ring in any instance may be adapted to be snapped into place, and thus attached, the same as bezel-rings and cap-plates 105 of watch-cases are now commonly attached, or to be otherwise fastened in place. The case-springs K K² are located in the recess M of the central shell, and one portion, R, of the length of each spring fits closely within and 110 between the concentric side walls of the recess, and at and along its other portion, S, in continuation of said portion R, is left free to act as a spring, and the springs are connected as usual—the one, K, to the hinged front cap 115 or plate of the case and at its hinge, so as to throw open said cap when the cap is released thereto, and the other, K², adapted as a catch to hold said cap closed until it is released.

T is a ring, Figs. 1, 3, 4, 5, 8, and 9, located 120 at the open side and within the recess of the central shell; to cover the springs therein against view when the ring closing said open side is removed. The ring T may be left loose or made fast by snapping or screwing it into 125 position.

The front bezel-ring, C, with its crystal D, as shown in all the figures except 2, 9, and 10, has a circular flange or rim, d, exteriorly screw-threaded, and this flange is entered and 130 screwed into the female screw-thread on the inner periphery of the riser f, which is at the

front O of the central shell or body, B. In all of the figures showing said front bezel and riser, as above stated, except Fig. 8, the threaded flange *d* of the bezel and the riser *f* are shown as so shaped relatively that said flange *d*, as the bezel is screwed into place, can pass between the outer periphery of the dial-plate L of the watch-movement and the inner periphery of the riser *f*, and in said Fig. 8 said threaded flange of the bezel and the riser are shown as so placed relatively that the flange of the bezel screwed into the riser enters only as far as the dial-plate, which in such case practically fills the riser, and is between the inner end of said flange *d* and the retaining-shoulder *g* of the movement-ring for the dial and the plate attached thereto of the watch-movement.

To allow of the entrance of the bezel-flange *d* between the dial-plate L and central shell-riser, *f*, as above stated, make the riser of a height equal or slightly exceeding the thickness of the dial and its plate, and of an internal diameter greater than the external diameter of said dial and its plate, and correspondingly increase the external diameter of said flange. For the bezel-flange to be entered into said riser without passing between the dial-plate and riser, as described, reduce the internal diameter of the riser and the external diameter of the bezel-riser from that rendered necessary for the entrance of said bezel-flange between said riser and said dial-plate, as above stated, and increase the height of the riser sufficiently to obtain a proper and requisite hold between the riser and flange when the latter is entered and screwed into the former.

In both forms of attachment of the front bezel to the front of the central shell or body above described the front bezel is shouldered both inside and outside of its flange, and when the bezel is screwed into place the outer shoulder is brought closely and tightly against the outer end of the riser of the central shell, and the inner shoulder is preferably suitably arranged to then be almost in contact, if not in contact, against the front face of the dial, but without pressure thereon. This front bezel, C, with its flange *d*, and the central shell, B, with its riser *f*, although described and shown to be attached together by screwing the former onto the latter, may, in lieu thereof, be constructed for the bezel-flange to be entered into and thus secured to the riser of the central shell by snapping it in, the form of construction of the two parts for so attaching it being well known; and, again, the bezel-ring may be hinged at one side to the central shell, so that by swinging it on said hinge it can be either entered into or withdrawn from the inside of the riser, as the case may be. It is preferable, however, to adapt the said bezel and central shell to be attached together by screwing the bezel into the shell, as particularly described.

The front bezel-ring, C, attached to the front

of the central shell or body, as above described, is covered or inclosed by the front cap or plate, G, hinged to the central shell, and otherwise arranged in relation to the case-springs as has been described, and as usual. As shown in Figs. 9 and 10, the front cap or plate, G, makes also the front bezel ring, C, to carry the front crystal, D, and in both views it is illustrated as screwed upon the outside of the riser *h* at the front of the central shell, B, and brought to a close seat against the flat front face of said shell. This front cap or plate carrying front bezel and crystal may be hinged to the central shell or snapped thereon, in lieu of being screwed thereon, as has been described; and, again, it is preferable to provide said cap or plate with a reflector, *k*, around the inside of its bezel, which flares toward the center and away from the inner surface of the crystal.

The back bezel-ring, E, as shown in all the figures except Figs. 1^A, 2, and 10, forms a part of the back of the central shell, B, which, if made separate from the shell, is, for the purpose of attaching it thereto and detaching it therefrom, adapted to be screwed or snapped into or otherwise fixed in position, as has been previously described.

In all the sectional views of the drawings except Fig. 1^A the watch-case at its back is shown as provided with the back plate or cap, H, and the outer edge, *l*, of this plate has a shoulder, *m*, produced from the upsetting of the metal of which the back plate is composed, in stamping out the back plate, or from turning up the metal making said back plate, or otherwise. This shoulder of the back plate is screw-threaded for the attachment of the back plate to the central shell by screwing it upon the riser thereof, and which is suitably screw-threaded therefor; but it, together with the back of the central shell, may be adapted for being attached together by snapping the one upon the other; or the back plate may be hinged to the shell, and thus with the central shell adapted for the back plate to be opened and closed.

From the construction of a watch-case in its several parts and their combination and arrangement together as has been described it is obvious, first, that the case, as a whole, can be most economically manufactured, as all of its parts, including its recessed central shell, B, whether or not it is combined in one piece with its movement-ring A, as described, can be stamped out in dies from sheet metal, substantially ready for immediate use, without further manipulation; second, that case-springs K, K² of greater strength and size and weight can be used than is possible in cases as heretofore constructed; and, again, as the central shell is provided with a recess, M, to receive said springs, which recess is adapted for them to be inserted at the outside of the shell, such springs can be made in advance and in quantities properly milled or swaged to fit said re-

cess, all of which greatly economizes in labor and trouble and time; third, that the location of said case-springs K K² within the central shell, as described, which is enabled to be done 5 because of the described recessed or chambered construction thereof, greatly stiffens and strengthens said shell, thereby allowing metal of a reduced thickness to be employed, and consequently securing a saving in the amount 10 of precious metal necessary for the case; fourth, that the making of the back bezel and back to central shell, B, in one piece, in lieu of in separate pieces, saves labor in manufacture and secures an improved and stronger bezel; 15 fifth, that the ring T, inserted within the recess M of the central shell, B, and covering the springs K K² therein, conceals them from view and from the entrance of dust or other deleterious matter and moisture to them when the 20 back bezel is removed, said bezel being made in one piece with the back of central shell; sixth, that the described attachment of the front bezel-ring closes the central shell of the case at its front most effectually against the entrance of dust or other deleterious matter and 25 moisture to the watch-movement, and at the same time secures a most neat finish to the front of the central shell, and requires less labor and cost in manufacture; seventh, that 30 the watch-case, as a whole, is most effectually made tight against the entrance of air, moisture, dirt, or other deleterious matters, and this result is more particularly insured under the present improved construction, from the fact 35 that the central shell and movement-ring are, in fact, completed and in use, one and the same piece of the case; eighth, that the making of the central shell or body recessed or chambered and making it with the movement- 40 ring in and of one piece substantially secures great economy in amount of metal necessary, while insuring all requisite stiffness and strength to said shell.

The winding-arbor a, Figs. 1 and 1^A, more 45 particularly, of the watch-movement at its square-shaped portion n, projecting beyond movement-ring A, enters into and engages with a correspondingly square-shaped socket of sleeve or arbor q. This sleeve or arbor q 50 at its outer end, r, is closed, and at its inner portion, t, it is provided with an external collar, u, which, with said inner portion, is arranged to turn and be interlocked within a correspondingly-shaped bearing, v, of the 55 movement-ring A. Again, the sleeve-arbor q, exteriorly at its portion w projecting beyond the movement-ring A, is made square-shaped in cross-section, and such portion at its extreme outer and closed end, r, enters for 60 a portion of its length into a correspondingly square-shaped socket, x, of a stem, y, of the pendant J, which stem is arranged to turn within and to be moved in and out of said pendant, and otherwise, as usual, and from its 65 inward movement to press against the catch and case-spring K², straddling the sleeve-arbor

q, and thereby to release it from the front cap or plate, G, for the same to be opened from the operation of the case-spring K. The stem y in its inward and outward movement 70 through the pendant moves by its square-shaped socket x along the outside of the sleeve-arbor q, and without necessarily turning it, and turning said stem in the proper direction within said pendant correspondingly turns 75 said sleeve-arbor, and through it the winding-arbor a, and thus the watch-movement can be and is wound.

In Fig. 3 is shown a modification in the connection between the push and winding stem 80 and the sleeve-arbor q; and it consists simply in entering said stem into said arbor q, instead of said arbor into said stem, and the sleeve-arbor is arranged to turn in but not to interlock with its bearing v of the movement-ring A; 85 otherwise the construction and arrangement of parts are the same as shown in Figs. 1 and 1^A, and the whole operate together as before described.

The winding mechanism above described 90 for the watch-movement enables said movement to be wound from the outside of the case and presents the slightest chance for the entrance of air, moisture, and other deleterious matter to the watch-movements at such part 95 of the watch-case, and to still further protect the watch-movement against said entrance of dust, &c, the knob z of the push-stem can be inclosed in a cap (not shown) screwed over and upon the outside of the pendant J at p. 100

The sleeve-arbor q may be arranged to be directly operated to turn the winding-arbor a, instead of through a turning-stem, y, and, as is plain, the in-and-out movement and the turning of the stem are independent of each 105 other.

The invention herein described it is not intended to limit to any particular watch-movements, by whatever name known; but it is to be applied to all such for which it is adapted. 110

Having thus described my invention, what I claim, and desire to secure by Letters Patent, is—

1. In a watch-case, a movement-ring or band, A, in combination with a recessed or chambered central shell or body, B, the two together constituting one piece, and the latter constructed for the attachment of the other parts to complete the case, substantially as described, for the purpose specified. 115

2. In a watch-case, a movement ring or band, A, and a recessed or chambered central shell or body, B, the two together constituting one piece, and the latter constructed for the attachment of the other parts to complete the case, in 120 combination with case-springs K K², arranged in the recess of said central shell, and with a front cap or cover of the case hinged to the front of said shell, and otherwise arranged in relation to said springs, and with a back cap or cover 125 applied to the back of said shell, substantially as described, for the purposes specified.

3. In a watch-case, a movement band or ring, A, surrounded by case-springs K K², for a hinged front cap or cover, G, which springs are confined in a recess or chamber, M, of a central body or shell, B, that of itself is constructed for said springs to be inserted in and removed from said recess at the outside thereof, and substantially as described, for the purpose specified. 55
- 10 4. In a watch-case, a movement band or ring, A, surrounded by case-springs K K², for a hinged front cap or cover, G, which springs are confined in a recess or chamber, M, of a central body or shell, B, that of itself is constructed for said springs to be inserted in and removed from said recess at the outside thereof, and for receiving a ring, T, to cover said springs, and substantially as described, for the purpose specified. 60
- 15 5. In a watch-case, a movement band or ring, A, in combination with a recessed or chambered central body or shell, B, the two together constituting one piece, and the latter constructed to open and close its said recess at the outside thereof, and for the attachment of the other parts to complete the case, substantially as described, for the purpose specified. 65
- 20 6. In a watch-case, a front bezel or crystal-cap, G, having a flange, d, in combination with a riser, f, at the front of the central shell or body, B, the two adapted for the cap to be entered into and secured to the riser, and in relation to the dial-plate of the movement, substantially as described, for the purpose specified. 70
- 25 7. In a watch-case, a plate or cap, G H, having a shoulder, m, at its outer edge, l, all made of one piece, substantially as and for the purpose described. 75
- 30 8. In a watch-case, a recessed central shell or body, B, in one piece with a ring or band, A, containing the watch-movement, which at its front and back is protected, substantially as described. 80
- 35 9. In a watch-case, a recessed central shell or body, B, in one piece with a ring or band, A, containing the watch-movement, in combination with springs K K² within the recess of said shell, and with a hinged front cap, G, and bezel-ring C, having crystal at the front of said shell, and said shell at its back protected, all substantially as described. 85
- 40 10. In a watch-case, a recessed central shell or body, B, in one piece with a ring or band, A, containing the watch-movement, in combination with bezel-rings— one at the front and the other at the back of said shell, substantially as described. 90
- 45 11. In a watch-case, a recessed central shell or body, B, in one piece with a ring or band, A, containing the watch-movement, in combination with bezel-rings at the front and back of said central shell, each having a crystal, and with a back cap or plate, H, substantially as described. 95
- 50 12. In a watch-case, a recessed central shell or body, B, in one piece with a ring or band, A, containing the watch-movement, in combination with springs K K² within the recess of said shell, with a hinged front cap, G, a back cap, H, and front and back bezel-rings, C E, of said central shell, each provided with a crystal, substantially as described. 100
- 55 13. In a watch-case, the combination of the movement-ring A, the angular winding-arbor a, the arbor q, connected with arbor a, and closing the opening in the movement-ring A for the arbor a, and a stem, y, adapted to engage with the arbor q, and to turn from the outside of the case and be moved in and out, substantially as and for the purpose set forth. 105
- 60 14. In a watch-case, the combination of the movement-ring A, the angular winding-arbor a, the arbor q, connected with arbor a, and closing the opening in the movement-ring A for the arbor a, a stem, y, adapted to engage with the arbor q, and the catch-spring for the front cap or plate, G, substantially as and for the purpose set forth. 110
- 65 15. In a watch-case, the combination, with the square-shaped arbor a of the watch-movement, of a square-shaped socket or sleeve arbor, q, engaged therewith, and interlocked by a collar, u, with and turning in a bearing, v, of the movement-ring A, of a stem, y, engaged with said arbor q, and turning within and adapted to be moved in and out of the pendant J of the watch-case, and of a catch-spring, K², for the front cap or plate, G, substantially as and for the purposes described. 115

In testimony whereof I have hereunto set my hand in the presence of two subscribing witnesses.
